ENGINE STARTER

James E. Buxton, Elmira, N. Y., assignor to Bendix Aviation Corporation, Elmira Heights, N. Y., a corporation of Delaware

Application August 2, 1945, Serial No. 608,515

8 Claims. (Cl. 74—7)

1

The present invention relates to an engine starting mechanism and more particularly to that type of starting mechanism in which the engine starter remains operatively connected to the engine until the engine is reliably self-operative.

It is an object of the present invention to provide an engine starting mechanism having novel means for maintaining the engine driving member in engagement with an engine member during the starting operation.

It is another object to provide such a device having a latch for maintaining the engine driving member in engagement with the engine member during the starting operation.

It is another object to provide such a device embodying a limiting or confining ring to prevent the latch from releasing in response to centrifugal force while the starting switch is closed.

It is another object to provide such a device in which the confining ring is operated in conjunction with the starting switch to hold the latch member in operative position until a true start of the engine is secured.

It is a further object to provide such a device in which the confining ring is a component part of the drive and is light in weight while being easy to assemble.

It is a further object to provide such a device in which the confining ring is concentrically and slidably mounted on an axially concentric cylindrical member of an engine starter so as to obtain reduction of vibration by dynamic balance and good alignment between the axis of the ring and the axis of rotation of the latch.

Further objects and advantages will be apparent from the following description and accompanying drawing, in which:

Fig. 1 is a side elevation partly in section of an engine starting drive embodying a preferred form of the invention, showing the latch and confining ring therefor in idle position, the electrical starting system being shown diagrammatically;

Fig. 2 is a view similar to Fig. 1 showing the starting drive and associated parts in cranking or operative position;

Fig. 3 is a view similar to Fig. 1 showing the starting drive in overrunning position with the latch moved outwardly into contact with the confining ring;

Fig. 4 is a cross-sectional view of the drive on the line 4—4 of Fig. 1 showing the latch in idle position;

Fig. 5 is a cross-sectional view taken on the

line 5—5 of Fig. 3 showing the latch in operative position; and

Fig. 6 is a perspective view of a fragment of a screw shaft illustrating the latching abutment and clearance space for the latch.

In Fig. 1 of the drawing, there is illustrated a shaft 1 which may be the extended armature shaft of an electric starting motor, not shown, supported at its inner end by a bearing 2 on the

starting motor and at its outer end by a bearing 3 within an extended housing 4 attached to the starting motor. Adjacent the starting motor, a drive head 5 is fixedly mounted on shaft 1 by any suitable means such as an anchor pin 6. A cup-shaped housing member 7 having a double-D

opening 8 therein is closely fitted to a corresponding double-D section 9 on the head 5 and bears against a shoulder 11 on the drive head which is so located that a radial flange 12 of the housing 7 is positioned over the pin 6 so as to lock the pin in assembled position. A lock wire 13 is seated in a groove 14 on head 5 in position to bear against the flange 12 and hold the housing 7 assembled on the head. An operating

member in the form of a screw shaft 15 provided with threads 16 and a flange 17 is journaled on the motor shaft 1, and a disc 18 is fixed as by welding or brazing at 19 on the end of the screw shaft against the flange 17. Yielding driving

means are provided between the disc 18 and housing 7 in the form of a block 21 of elastic material such as rubber loosely fitting the interior of the housing and adapted to be compressed between the flange 12 and said disc.

An engine driving member in the form of a pinion 22 is slidably journaled on the shaft 1 for meshing engagement with an engine member such as a fly-wheel ring gear 23 of the engine to be started. Axial and rotational movements are

imparted to the pinion by a control member in the form of a nut 24 threaded on the screw shaft 15 and fixed as indicated at 25 in the end of a barrel 26 by any suitable means such as brazing. A separable driving connection is provided between the barrel 26 and pinion 22 in the form of a dental clutch 27 which is made operative by the final axial movement of the nut 24 after the meshing movement of the pinion has been arrested. The driving plate 28 of the clutch 27

is joined to the barrel 26 by lugs 29 on the plate fitting within slots 31 in the barrel and held therein by a lip 32 on the barrel spun over a ring 33. A driven clutch plate 34 is fixed to the pinion 22 by suitable means such as brazing as shown at 35, and is provided with dentals 36

mating with dentals 37 on plate 28. Clutch plates 28 and 34 are normally held out of engagement by the compression spring 38, the separation of the plates being limited by a thimble 39 having a flange 40 at one end forming a stop for the driven clutch member 34, and retained in the end of the barrel 26 by means of a peripheral flange interposed between driving clutch plate 28 and ring 33.

According to the present invention, means under the control of the operator are provided for maintaining the pinion 22 in operative engagement with the engine gear 23 until the engine is reliably self-operative. As best shown in Fig. 4, this means is in the form of a latch 41 pivoted at 42 on the control nut and urged into engagement with the screw shaft by a torsion spring 43 so as to automatically latch the control nut 24 to the screw shaft 15 as the point 44 of the latch drops behind an abutment surface 45 on the screw shaft. This abutment 45 is so located on the threads 16 as to enable the latch to engage it when the yielding driving member 21 is in relaxed condition and the clutch dentals 36, 37 are separated. For this purpose, one of the threads 16 on the screw shaft 15 is cut away to form a recess at 46, as best shown in Fig. 6, which permits the point of the latch to bear on the root diameter of the thread during the final movement of the control nut which closes the clutch 27.

Manually controlled means are provided for holding the latch in operative position in the form of a confining ring 47 constructed as an extension of a sleeve member 48 which is slidably mounted on the cylindrical housing 7. When ring 47 is in the plane of rotation of the latch during the starting operation, the latch is not permitted to fly outward under the influence of centrifugal force caused by the rotation of the barrel 26, and accordingly maintains pinion 22 in mesh with the engine gear 23 regardless of the speed of rotation of the parts.

Unitary means in the form of a push-rod 49 under the control of the operator are provided for moving the sleeve 48 into operative position and concurrently closing a starting switch 51. A shift fork 52 is fixedly mounted on the push rod 49 by means of a set screw 50 and projects downwardly through an opening 53 in the housing extension 4. The arms 54 of the fork support rollers 55 within an annular channel 56 in a shift collar 57 which is mounted on the sleeve 48. Lugs 58 and a snap lock ring 59 are provided at the sides of the collar 57 to longitudinally confine it on said sleeve. Push-rod 49 is journaled in brackets 61 and 62 and a bridging member 64 of the starting switch 51 is slidably mounted on said rod and normally held against a stop shoulder 63 thereon by means of a spring 65 seated on the shift fork 52. Electrical energy is supplied to the starting motor SM by a battery 66 which is grounded at 67 and connected by a lead 68 to contact 69 of the starting switch, the opposite contact 71 thereof being connected by a lead 72 to the motor SM which is grounded at 73 to complete the starting circuit.

The longitudinal travel of the push-rod 49 is preferably limited by a stop collar 74 (Fig. 2) fixed thereon in position to abut against the bracket 61 when the rod is so positioned as to place the confining ring 47 in the plane of the latch 41 when the parts are in cranking position.

In operation, the operator either directly or indirectly moves the push-rod 49 to the right in

Fig. 1 to close the starting switch 51, thus energizing the motor SM which rotates the screw shaft 15. Control nut 24 and the parts associated therewith including latch 41 are thereby traversed to the right, ahead of the sleeve 48 which is moved by the shifting fork 52. Further movement of said fork compresses the spring 65 and moves the shoulder 63 away from the bridging switch member 64 until the motion is arrested by the stop collar 74. Immediately after the latch 41 is fully traversed to operative position, the ring extension 47 follows and covers it, thereby confining it against outward movement from latched position as long as the operator holds the push-rod in shifted position. When the engine fires, the acceleration of the pinion 22 by the engine gear 23 is transmitted through the clutch 27 to the control nut 24 whereby the nut moves back on the screw shaft 15 permitting the clutch to be opened by spring 38 so as to allow the pinion to overrun freely. The backward movement of the nut is limited, however, by the engagement of latch 41 with the abutment 45, which engagement is positively maintained by the confining ring 47 so as to hold the pinion in mesh with the engine gear.

If the engine does not continue to be self-operative, the operator maintains the rod 49 in starting position with the ring 47 in the path of rotation of the latch 41 and cranking of the engine will be resumed as soon as the engine slows down to a speed corresponding to that of the starting motor. When reliable operation of the engine is secured, the operator retracts the push-rod 49 to first permit the latch 41 to move out by centrifugal force and release the pinion, and then to open the switch 51 to thereby deenergize the starting motor.

Although but one embodiment of the invention has been shown and described in detail, it will be understood that changes may be made in the form and arrangement of the parts without departing from the spirit of the invention as defined in the claims appended hereto.

What is claimed is:

1. In an engine starting mechanism, a motor shaft, an operating member mounted thereon to rotate therewith, an engine driving member slidably journaled on said shaft for movement into and out of engagement with a member of an engine to be started, means including a control member and a clutch between said operating and engine driving members for transmitting axial and rotational movement from the operating member to said engine driving member, releasable means on said control member for maintaining said engine driving member operatively connected with said engine member and means under the control of the operator for confining said releasable means.

2. In an engine starter, a motor shaft, a screw shaft mounted thereon to rotate therewith, a pinion slidably journaled on said motor shaft for movement into and out of engagement with a member of an engine to be started, means including a control nut and a clutch between said screw shaft and pinion for transmitting axial and rotational movement from the screw shaft to said pinion, means including a latch on said control nut for holding the pinion in mesh with said engine gear, and manually controlled means for holding the latch in operative position regardless of the rotational speed of the pinion.

3. In an engine starter, a motor shaft, a screw shaft mounted thereon to rotate therewith, a

pinion slidably journaled on said motor shaft for movement into and out of engagement with a member of an engine to be started, a control nut threaded on said screw shaft and means including a clutch between said nut and pinion for transmitting axial and rotational movement from the screw shaft to said pinion, a centrifugal latch pivoted on the control nut, means normally pressing the latch against said screw shaft, said screw shaft having an abutment surface cooperating with said latch to hold the pinion in meshed position, and a ring member movable by the operator into the plane of rotation of said latch to prevent delatching thereof.

4. In an engine starting mechanism, a starting circuit including a motor and a starting switch, a motor shaft, a screw shaft mounted on the motor shaft and driven therefrom, a pinion slidably journaled on said motor shaft for meshing with and rotating an engine gear, means for actuating the pinion including a nut member on said screw shaft, and a clutch connection between said control nut and pinion made effective by the final forward movement of said control nut; a latch member and a spring member for normally holding the latch member in contact with said screw shaft, both members being mounted on said control nut and cooperating with an abutment on the screw shaft to keep the pinion meshed with the engine gear, said latch being released by centrifugal force; and a ring for preventing unlatching of said latch, and unitary actuating means for moving said ring out of the path of rotation of said latch and simultaneously releasing said switch.

5. In an engine starting mechanism, a starting circuit including a motor and a starting switch, a motor shaft, a screw shaft mounted thereon and driven therefrom, a pinion slidably journaled on said motor shaft for meshing with and rotating an engine gear; means including a nut member on said screw shaft for actuating said pinion; a torsional connection between said control nut and pinion made effective by the final forward movement of said control nut, means for automatically latching said pinion in mesh with said engine gear, said means being responsive to centrifugal force for unlatching said pinion, an annular member for preventing unlatching of said pinion, and manually controlled means for actuating said annular member in timed relation to the operation of said starting switch to release said latching means before the starting switch is opened.

6. In an engine starting mechanism, a motor shaft, a housing member fixed thereon, a screw shaft journaled on said motor shaft and having a yielding driving connection to said housing, a pinion slidably journaled on said motor shaft for meshing with and rotating an engine gear, a control nut threaded to said screw shaft and a torsional connection including an enclosure member and a clutch between said nut and pinion, a

latch pivoted on said control nut and an abutment on said screw shaft for said latch to maintain said pinion in meshed position, and a sleeve under the control of the operator journaled on said housing and having an extension forming a confining ring for controlling said latch.

7. In an engine starting mechanism, a starting circuit including a motor and a starting switch, a motor shaft, a housing member fixed thereon, a screw shaft journaled on said motor shaft and having a yielding driving connection to said housing, a pinion slidably journaled on said motor shaft for movement into and out of mesh with an engine gear, a control nut mounted on said screw shaft and means including a barrel member and a clutch fixed to said barrel member for actuating said pinion from the screw shaft, a torsion spring and a latch inwardly biased thereby, both spring and latch being mounted on said control nut for keeping said pinion in mesh with the engine gear, an axially movable sleeve having an integral ring portion journaled on said housing for locking said latch in operative position during the starting operation, and unitary means for moving said sleeve and starting switch in unison.

8. In an engine starting mechanism, a starting circuit including a motor and a starting switch, a motor shaft, a housing member fixed thereon, a screw shaft journaled on said motor shaft and having a yielding driving connection to said housing, said screw shaft being provided with a cut-away portion on one of its threads terminating at one end in an abrupt shoulder, a pinion slidably journaled on said motor shaft for movement into and out of mesh with an engine gear, a control nut on said screw shaft for actuating said pinion from the screw shaft, a centrifugally responsive latch and a spring for urging said latch toward the center of rotation of said screw shaft, both spring and latch being mounted on said control nut for retaining said pinion in mesh with the engine gear during cranking of the engine and preventing drifting of said pinion from idle position when said starting mechanism is inoperative, a thread of said screw shaft having a recess forming a radial abutment surface for contacting said latch in latch position, an axially movable sleeve journaled on said housing for preventing radial unlatching movement of said latch during the starting operation and manually controlled unitary means for moving said sleeve and switch in timed sequence.
